CLAIM

The ornamental design for a planter, as shown and described.

DESCRIPTION

FIG. 1 is a front elevational view of a planter showing my new design;

FIG. 2 is a rear elevational view thereof;

FIG. 3 is a side elevational view taken from the left of FIG. 2, the said opposite being substantially identical;

FIG. 4 is a top plan view thereof;

FIG. 5 is a bottom plan view thereof;

FIG. 6 is a perspective view thereof, the plants being shown in broken lines for illustrative purposes only.

FIG. 6

FIG. 4
